United States Patent Office

Des. 186,543
Patented Nov. 3, 1959

186,543

COMBINED LOCKET, COMPACT, AND LIPSTICK HOLDER

Herbert Chaikin, Long Beach, N.Y.

Application April 30, 1959, Serial No. 55,711

Term of patent 3½ years

(Cl. D45—15)

Fig. 1

Fig. 2

Fig. 3

Fig. 4

Fig. 5

Fig. 6

Fig. 1 is a front elevational view of a combined locket, compact and lipstick holder, showing my new design;

Fig. 2 is a rear elevational view;

Fig. 3 is a side elevational view seen from the left of Fig. 1;

Fig. 4 is a side elevational view seen from the right of Fig. 1;

Fig. 5 is a top plan view; and

Fig. 6 is a bottom plan view thereof.

I claim:

The ornamental design for a combined locket, compact and lipstick holder, as shown.
